Des. 183,541

Patented Sept. 16, 1958

183,541

COMBINED FLEXIBLE BOTTLE AND DISPENSING CLOSURE CAP

Carl M. Plochman, Jr., Winnetka, Ill., assignor to Plochman & Harrison, Chicago, Ill., a partnership

Application May 22, 1958, Serial No. 51,024

Term of patent 14 years

(Cl. D58—8)

Fig. 2 is a rear perspective view in exploded condition.
I claim:

The ornamental design for a combined flexible bottle and dispensing closure cap, as shown.
